UNITED STATES PATENT OFFICE.

EARL G. GUNN, OF DETROIT, MICHIGAN.

MULTICYLINDER ENGINE.

1,260,375.

Specification of Letters Patent. Patented Mar. 26, 1918.

Application filed April 3, 1916. Serial No. 88,548.

To all whom it may concern:

Be it known that I, EARL G. GUNN, a citizen of the United States of America, residing at Detroit, in the county of Wayne 5 and State of Michigan, have invented certain new and useful improvements in Multi-cylinder Engines, of which the following is a specification, reference being had therein to the accompanying drawings:

- 10 The invention relates to multi-cylinder engines of the so-called L-type, and it is the object of the invention to facilitate the casting of the block and to permit the forming of the same out of different materials.
- 15 In the present state of the art it is common to form multi-cylinder L-type motors *en bloc*, and for lightness these have been made of aluminum. It has been found difficult, however, to form the complex cored structure from such material, and further this material is unsuitable for wearing surfaces, such as the inner face of the cylinder and the valve seats. The cylinders can be readily bushed with sleeves of a suitable
- 20 wearing material, such as cast iron, but the bushing of each of the valve seats would greatly complicate the structure. I have therefore devised a construction in which the cylinders and the L-extension thereof 25 are made in separate sections, the cylinders being preferably formed of aluminum and the L-portions of cast-iron. The substitution of cast-iron for the latter part will but slightly increase the weight and will pro-
- 30 vide suitable material for the valve seats without the necessity of facing or bushing the same. On the other hand, the casting operation is greatly simplified, as the cores for forming the water-jacket surrounding
- 35 the cylinder are readily supported on the side which adjoins the L-section and the casting of the latter section is also simplified.

In the drawings:

Figure 1 is a cross-section through an engine embodying my invention;

Fig. 2 is a plan view thereof with the head or cover-plate removed; and

Fig. 3 is a side elevation.

A A', etc., are a plurality of cylinders of

a multi-cylinder engine, which are cast *en bloc*. As shown the block includes in addition to the cylinders and their water-jackets a portion B forming the upper section of the crank case, but the head C and L-section D are formed of separate members. This 55 permits of supporting the cores for forming the annular chambers E of the water-jacket from the side which adjoins the extension D. This side is provided with a marginal bearing portion F, which is machined for engagement with a corresponding marginal bearing G on the L-section, the parts being secured together by suitable means, such as studs H at distributed points in the area thereof. As has been stated the 60 section D is preferably formed of cast-iron and is suitably cored to form the inlet and exhaust ports I J and the water chamber surrounding the same and which communicates with the chambers E. The head D 70 is extended to cover both the cylinder block and the L-extension.

With the construction as described the manufacturing cost is reduced, and the advantage of the cast iron and the aluminum 75 constructions are combined. Thus by using cast-iron bushings L for the cylinders, and forming the L-section of cast-iron good wearing surfaces for the working parts are obtained, while the use of aluminum for 80 the greater portion of the structure reduces the weight over an all cast-iron construction.

What I claim as my invention is:

1. In an engine, the combination with a cylinder formed of a relatively light material, of an L-extension for said cylinder formed from a heavier and harder material, mounted upon and positioned by said relatively light material.

2. In an engine, the combination with a plurality of cylinders formed of relatively hard material and cast *en bloc*, of an L-extension formed of relatively heavy material, common to all of said cylinders and formed of a separate section attached directly thereto.

3. In an engine, the combination with a plurality of cylinders cast *en bloc*, of an L-

extension common to said cylinders, separately formed and attached thereto, and a separate head covering all of said cylinders and the L-extension thereof.

5. In an engine, the combination with a cylinder formed of a relatively light material provided with a water jacket open at

one side thereof, of an L-extension for said cylinder formed of a relatively hard material and provided with a water jacket closing said open side of the cylinder water jacket.

In testimony whereof I affix my signature.

EARL G. GUNN.
